UNITED STATES PATENT OFFICE.

CHARLES HARRIS EMERSON AND WILLIS HENRY WETMORE, OF BURLINGTON,
VERMONT; SAID WETMORE ASSIGNOR TO SAID EMERSON.

TOBOGGAN.

SPECIFICATION forming part of Letters Patent No. 380,875, dated April 10, 1888.

Application filed August 17, 1887. Serial No. 247,212. (No model.)

To all whom it may concern:

Be it known that we, CHARLES HARRIS EMERSON and WILLIS HENRY WETMORE, both of Burlington, county of Chittenden, and State 5 of Vermont, have invented new and useful Improvements in Toboggans; and we do hereby declare that the following specification, taken in connection with the drawings furnished and forming a part of the same, is a clear, 10 true, and complete description of the several features of our invention.

In that class of coasting-toboggans constructed of long thin flexible strips of wood the best methods of fastening the same securely 15 to the cross-bars heretofore in use are shown and described in Patent No. 358,601, dated March 1, 1887, issued to Charles H. Emerson, then of Yonkers, New York, now of Burlington, Vermont, and one of the applicants herein 20 named, and are improved, as shown in subsequent applications by the same inventor, filed, respectively, on January 17 and April 28, 1887. By the former method (covered by Patent No. 358,601) screws or rivets are required 25 to be used, extending vertically into the thin slats forming the bottom of the coaster, while in all methods heretofore in use the hand-rail-fastener bolts pass entirely through the two outside slats, requiring large countersunk 30 holes to receive the bolt-heads; but in a coaster of this class a perfectly smooth and entirely unbroken bearing-surface admitting of a high polish is very desirable; and, further, in coasters of this class, which are very long and 35 vertically slender, a very high degree of speed is attained, and various steering attachments have been devised; but, so far as we are informed, they are invariably to be operated by hand or foot power. In all these it has proved 40 that they are not quick enough of application in practice to effect the purpose required, principally because the person using such an apparatus must first see the actual veering of the coaster, and then, using his judgment, apply 45 the steerer; but by reason of the excessive swiftness of the coaster this operation is invariably too slow to do much good.

The object of our invention is to provide a more perfect operation of the clips or fasteners described and illustrated in the Patent No. 50 358,601, before mentioned, and in the applications aforesaid by Charles H. Emerson, and to do away entirely with the use of screws or

rivets, or, in fact, any form of fastening whatever that must pass through or vertically into 55 any part of any slat forming or a part of the running-surface of the toboggan. We accomplish this principally by means of horizontal pins passing through portions of said clips or fasteners and into the coincident edges of the 60 slats.

A further object is to provide an automatic or self-steering attachment for toboggans or coasters which shall be instantaneous in its action, with little friction, and which shall preclude all possibility of false or useless attempts 65 at steering on the part of the person using the coaster.

After describing the drawings illustrating in detail our improved toboggan, the features 70 deemed novel will be specified in the claims annexed hereto.

In the accompanying drawings, Figure 1 is a cross-section view at the rear cross-bar, embodying all the principal features of our invention. Fig. 2 illustrates the old clip-fastener covered by said Patent No. 358,601 applied to a pair of slats with common screws. Fig. 3 in three views illustrates the improved clip with a lip turned down and punched to 80 hold the horizontal pin. Fig. 4 illustrates the new improved clip applied to a pair of slats. Fig. 5 in three views illustrates a modified form of the clip provided with flanges to enter grooves in the under side of cross-bar, and 85 an embossment with slot for a nut or bolt head, and intended for use upon the two outside slats and to preclude the necessity of putting the bolt through the slat. Fig. 6 illustrates a double-threaded nut, by means of which the 90 hand-rail-holder bolt is secured to the slat as another means of avoiding boring through the slat. Fig. 7 (three views) shows still another form of fastener for intermediate slats, using the separate horizontal pins in their edges, 95 but particularly when it is desirable to use a solid cross-bar. Fig. 8 illustrates another modified form of fastener with horizontal ends for pins and the twisted fold of the wire for a hook to engage a stud driven transversely 100 through the sides of a slotted cross-bar. Fig. 9 shows still a different form of the clip or fastener with ends or prongs for pins, but stamped out of sheet metal in one piece, and to be twisted half around after passing through 105 a slot in the cross-bar to lock slat and cross-

bar together. Fig. 10 illustrates another form of sheet-metal fastener stamped out at one operation in one piece, with flat flanges instead of pins to enter the edges of slats. Fig. 11 in two views illustrates the automatic steering attachment in its preferred form. Fig. 12 shows a modified form of the attachment with rolling blades or edges. Fig. 13 illustrates a compact form of attachment with solid runner. Fig. 14 shows the blades of the attachment disconnected and applied separately.

When, with the use of the improved clips and horizontal pins, a toboggan is constructed as herein described and illustrated—viz., so that no slat-fastener shall pass through or vertically into any part of any slat forming the bottom of the toboggan—it will be readily seen that another important object besides an unmarred running-surface is attained, which is that no amount of swelling and shrinking of the slats, caused by the alternate wetting of them by snow-water and drying out when not in use, will in any manner impair the grip of the improved clips upon the parts they bind together; nor will they allow the slats to warp each other out of shape in swelling together, as often occurs when screws or rivets are used, and particularly when they are rigidly held against any lateral movement by the hand-rail-holder bolts passing through the outside slats. The usual method of avoiding this warping from swelling when wet is to leave wide cracks between the slats; but this is highly objectionable by leaving free access to snow and bits of ice that stick and retard the speed and wet the under side of the cushion. By the use of our improved clips the slats may be placed tightly together, and when they swell from wetting they expand laterally and remain in the same plane.

The improved clips may be made in a great variety of forms in sets or pairs, or singly, without in any manner affecting our invention. The clips or binders shown in Figs. 3, 4, and 7 are in what we consider their best forms for use on the inner or intermediate slats. Those shown in Figs. 3 and 4, particularly, are formed of sheet metal of suitable thickness having a flat back, *a*, and lugs *a'* to embrace the cross-bar *B*, and with a lip, *d*, turned down and punched for the pin *e* to pass through it and into the adjoining slats; but for use on the two outside slats a somewhat different form of clip or fastener is desirable in order to secure the slat and the hand-rail-holder bolt together without the necessity of putting this bolt through the slat, as heretofore, and at the same time to grip both edges of the same slat. We accomplish this by the form of clip illustrated in Fig. 5, made of sheet metal, with lips *d d* at each end, through which the pins *e e* enter the slat, as shown in Fig. 1. The longitudinal flanges *F F*, Fig. 5, are formed by turning up the edges of the clip to an acute angle, and serve to stiffen the clip and to fasten it to the cross-bar by entering grooves made to receive them in the under side of the cross-

bar. A shallow indenture or embossment is shown at *E* with a slot through which the bolt may enter to engage the nut confined under it. The lower side of the cross-bar is rabbeted, so it will slide over the nut *G*. Thus with the two forms of clips shown in Figs. 1, 3, 5 all the slats are firmly bound to the cross-bar and a limited lateral movement provided for, as well as the securing of the rail-holder at the same time, and no fastening permitted to enter vertically any slat. With these fastenings we prefer the cross-bar *B* in two pieces slightly wedge-shaped, as shown in Figs. 1 and 4, because we thus readily obtain just the degree of tightness required before boring for the rail-holder bolt; but this is not needed for more than every other alternate cross-bar in the series forming the toboggan, and for the others we use solid cross-bars (in one piece) and the form of fastener shown in Fig. 7. This is a simple screw-pin or rivet to enter the cross-bar at proper intervals, and has a lip for the horizontal pins exactly like the other forms of clips.

In our improved toboggan the hand-rail holder *C*, Figs. 1, 5, is novel in construction, being formed of a block of wood, through which the half-round wire staple is passed, which embraces the hand-rail and is clinched on the under-side. A countersunk perforation through the center of the block receives and holds the bolt *D*. This combination is stronger, lighter, and cheaper than any of those in present use; but the loop-fastener *H* may also be used without the aid of the bolt *D* and without in any way affecting our invention. In such case the extremities of the wire loop, instead of being clinched on the under side of the block *C*, have feet or points turned upon them just long enough to permit their introduction into the holes bored to receive them, and passing through the block and into the cross-bar; or, in fact, the holes may pass through the cross-bar as well and into the slat. We prefer to make the holes deeper than the length of the loop leg or end to be used. The feet are then more surely forced into the wood at the sides of the holes, when the wedges or dowels which we use for this purpose are driven in behind the leg of the loop to tightly fill the holes. It will be readily seen that by this means the parts are tightly bound together without the use of bolts or screws, and the purposes of our invention more perfectly realized.

Another novel feature of our improved toboggan is clearly shown in Figs. 1, 11, 12, 13, and 14, and consists in an automatic or self-steering attachment which may be readily applied to any toboggan.

In Fig. 11 the self-steerer is attached to the toboggan at the rear end of the center slat. The skate-like edges *k k'* of the runner *K* protrude slightly through slots in the slat, made parallel with the edges of the slat, with the rounded end *m'* pointing forward. The spring *n* keeps the blade or edges of the steerer gently pressed downward, and the post *h* serves to

keep both the runner K and the spring n in their proper positions. The hole in the center of the back of the runner K is made to fit the pin h loosely, so that the runner may have 5 both a free upward and oscillating movement, as required. With this construction it will be readily seen that with the toboggan making a straight forward movement the edges of the steerer k' k' would bear evenly upon the ice, 10 and like a skate-runner, which it resembles, present the minimum of frictional resistance; but the instant that any sluing motion is given to the toboggan the sharp edge of the self-steerer scrapes or cuts into the ice and 15 presents its whole breadth against the side movement, and the more forcible this movement is the more firmly the edge k' of the steerer on the side toward which the sluing movement tends cuts into or seizes upon the ice, 20 when the position of the self-steerer would be as shown by the dotted lines, Fig. 11. This aids to instantly check the undue sluing and guide the toboggan by an easy curve to its forward movement with the least possible retardation 25 of that movement, and the self-righting steerer falls back to its normal position as the side pressure decreases. We prefer this form of the self-steerer illustrated in Figs. 1 and 11; but a very wide variety of forms may be used 30 without in any manner affecting our invention.

Figs. 12 and 13 show the steerer with two pivots and two springs to regulate the oscillating movement, the runner being cast solid 35 and narrow, the whole, in fact, presenting the minimum of compactness, and this again by a little changing may be made to act as a rotary steerer by simply introducing a solid roller slightly concave at its periphery to furnish the 40 sharp edges k' k', and without departing from our invention.

Still another form is shown in Fig. 14, and here the steering-edges are widely separated, being in fact disconnected from each other 45 and attached independently on the two outer sides of the toboggan, respectively.

We are aware that vehicles for use upon ice have been made with propeller-wheels in various designs and constructions; but our oscillating and rotating steerer-blade is not in any 50 sense a propeller-wheel. In fact, on account of its peculiar construction and application to the vehicle, as herein described, it cannot be used as such, nor can wheels of propulsion or 55 conveyance properly as such perform the functions of our steering device.

We are also aware that steering or guiding runners have been used; but in every case they are ordinary runner which must be operated 60 by hand or foot power to have any effect in determining the desired course of the vehicle. We therefore disclaim in our construction of an oscillating and rotating steering device the 65 functions of wheels of conveyance or propulsion, our invention in this respect being essentially a self-acting guide or automatic steerer for a vehicle propelled by gravity.

Having thus described our invention, we claim as new and desire to secure by Letters Patent—

1. In a toboggan or coaster, the combination, as herein described, of the slats and the cross-bars with the fasteners, which secure the slats, without the aid of rivets or screws or other fastenings passing vertically into the 75 slats, by means of pins passing through projecting lips of the fasteners and horizontally into the edges of the said slats.

2. In a toboggan or coaster, the combination of the slat and the cross-bar and the hand-rail-holder bolt with the improved form of clip, which grasps both edges of the same slat, substantially as described, whereby the parts named are securely united without putting the said bolt through the slat, as heretofore. 85

3. In a toboggan or coaster, the combination of the slat and the cross-bar and the bolt D with the double-threaded nut g, substantially as described.

4. In a toboggan or coaster, the combination of the block C, interposed to elevate the hand-rail I above the cross-bar B, with the bolt D and the fastener H, substantially as described. 90

5. In a toboggan or coaster, the combination of the hand-rail fastener H, provided with feet to be wedged into the sides of the holes bored to receive them, with the block C and cross-bar B. 95

6. In a toboggan or coaster, the combination of the fastening-clips and the slats with the cross-bars made in two wedge-shaped pieces, by which means more or less flexibility is secured, as required, while the whole are quickly and tightly united, substantially as 100 herein described and illustrated.

7. In a toboggan or coaster, the combination of the bottom slat and the cross-bar with the eyebolt F' F² and the pin e, substantially as and for the purposes described herein. 110

8. In a toboggan or coaster, the combination, as herein described and illustrated, of a steering device having one or more revolving or oscillating runner-blades shaped and constructed so as to automatically resist and prevent a side or sluing movement. 115

9. The combination, in a toboggan or coaster, of a self-acting steering device formed of one or more runners attached rigidly to the bottom of the coaster and depending upon the 120 concave shape or sharp edges alone to resist a sluing movement.

10. In a toboggan or coaster, the combination of an automatic steering device provided with skate-action runners, and the controlling-springs n n' n², and the securing or covering clip a, substantially as herein described and illustrated. 125
